UNITED STATES PATENT OFFICE.

JULIUS WILHELM VON PITTLER, OF BERLIN, GERMANY.

ROTARY ENGINE.

No. 894,391.

Specification of Letters Patent.

Patented July 28, 1908.

Application filed June 6, 1907. Serial No. 377,513.

To all whom it may concern:

Be it known that I, JULIUS WILHELM VON PITTLER, a subject of the King of Prussia, residing at 6/7 Schiffbauerdamm, Berlin, Germany, have invented certain new and useful Improvements in Rotary Engines, of which the following is a specification, reference being had to the accompanying drawings, forming a part hereof.

10 This invention relates to engines, pumps and the like in which there is a rotating member provided with sliding blades or pistons and having annular grooves athwart which blades are arranged to slide and in each 15 of which there is provided a fixed abutment which forms with the blades working-chambers within the grooves.

According to the present invention the blades or pistons of mechanism of this kind 20 are controlled by cam surfaces acting on their end surfaces. By this means it is possible with perfect guiding, to use the spaces between the rotating member and the casing as further working-chambers. To the known 25 method of guiding the blades by means of rollers arranged on the slides and running in cam-grooves in the casing, the method of guiding above mentioned is much to be preferred, since the rollers as well as their guide- 30 grooves, in the rapid motion of the blades round the casing or cylinder, are subjected to such excessively rapid wear that this system of guiding is practically useless.

The guiding of the blades or pistons in rotary engine, pump or the like mechanism on cam-surfaces on the casing is known *per se*, but its application to a mechanism of the present kind, with working-chambers provided in annular grooves in the rotating 40 member, is new.

The invention further consists in a special arrangement of the grooves in the rotating member which offers material advantages over the known arrangements, as will be seen 45 hereinafter.

Figures 1 and 2 illustrate in longitudinal and transverse section respectively, one embodiment of the invention consisting of a motor in which the pistons or blades are 50 axially movable and are arranged between two parallel surfaces by which they are moved and guided. Fig. 3 is a development of these surfaces, showing the periphery of the piston unrolled in a plane; Figs. 4 and 5 are 55 similar views in which the blades are radially movable; Fig. 6 is a view similar to Fig. 4 in

which the blades are moved in both directions solely by a fluid pressure medium, and Fig. 7 is a development of still another form of the invention.

Referring first to Figs. 1 and 3, the motor here illustrated has four pistons or blades 2 which are slidably axially in the rotary member 1 inclosed within a casing 5. The side walls of the casing are provided with parallel 65 curved surfaces 3, 4 between which the pistons are arranged and by which they are moved and guided. These surfaces form, with the rotary member and the pistons, working chambers 6, 7; assuming that the 70 rotary member and blades rotate in the direction indicated by the arrow 17 in Figs. 2 and 3, 8 and 10 are the inlet ports and 9 and 11 are the outlet ports.

In the periphery of the rotating member 75 are cut or otherwise formed one or more grooves 12 and athwart these grooves the piston-blades are arranged so as to slide transversely across the same as the ends of the blades travel upon the parallel surfaces 3 80 and 4. Within each groove is an abutment 13 entirely closing the same and which is secured to the casing. The pistons are cut or otherwise formed with recesses or openings 16 according to the number of grooves, which 85 recesses are brought into register with the corresponding grooves as the piston or pistons reach and pass the abutments. There is thus always between one of the blades and each end face of each abutment, a working 90 chamber which varies with the movement of the blade. In the case of a pump the chambers situated on the right hand of the abutment (Fig. 3) will be pressure chambers and those on the left hand of the abutment will 95 be suction chambers and 14 and 15 will be respectively the inlet and outlet ports.

Referring to Figs. 4 and 5, the same reference characters have been used as in describing the form shown in Figs. 1 to 3, to indicate 100 corresponding parts. In Figs. 4 and 5 the grooves are turned concentrically in the end surfaces of the rotating member. Accordingly the blades are radially movable and the parallel surfaces 3, 4 are formed, one on an 105 inner fixed sleeve surrounding the shaft of the rotating member and the other in the cylindrical portion of the casing. This arrangement presents considerable advantages as compared with the arrangement in which the 110 grooves are provided in the peripheral surface of the rotating member and wherein the

blades move axially. With a constant width of said grooves, the working chambers become larger as the grooves are made nearer to the exterior or periphery of the rotating member. This property is of great importance when employing the mechanism as a multiple-expansion engine, since in conducting the working fluid through the concentric working chambers in the order from the interior to the exterior, the successive working chambers increase in capacity as required. This arrangement of the grooves is moreover of importance for motors of automobiles and generally for engines which are to run at varying speeds with the turning moment varying in inverse proportion. Assuming that the mechanism is used as a motor and that a constant current of a fluid under pressure is conducted through the mechanism and moreover that each groove of the mechanism can be inserted separately into the fluid current, it is clear that the speed of rotation will be lower if a groove lying farther towards the exterior be used as the working-chamber, while at the same time the turning moment increases in accordance with the larger radius. Since two or more working chambers can also be used together in different combinations, a large number of different speeds can be obtained with correspondingly varying turning moments. A further advantage of the construction with radially movable blades consists in that when controlling the blades by means of cam-surfaces arranged on the casing, these surfaces are of simple curvature, while when employing axially movable slides the cam-surfaces are screw-shaped.

In the form shown in Figs. 4 and 5 it will be observed (Fig. 5), that there are two sets of pistons, one set at each end of the machine. With this construction, the rotating member is better balanced. Furthermore it will be noted that both sets are arranged symmetrically with respect to each other. It will be obvious, however, that it is not necessary to provide two sets of pistons or to arrange both sets symmetrically.

In Fig. 6 there are no working chambers 6, 7 formed by the pistons, rotating member and casing, or by the pistons, rotating member and an inner fixed sleeve. The pistons are arranged to be moved wholly by a fluid pressure medium and do not travel upon any curved surface, as in the case of the embodiments shown in Figs. 1 to 5 inclusive. For this purpose, the inner ends 22 of the pistons are made slightly wider and the inner portions 23 of the slots of the rotating member, in which the inner ends of the pistons work, are correspondingly widened. Into the outer ends of these widened portions of the slots fluid pressure may be introduced through a channel 26 in such a way as to normally hold the pistons inwardly so that their openings will not register with the

grooves in the rotating member. Just before they reach the fixed abutments, however, they pass over the channel 26 and the inner ends of the widened portions of the piston slots are brought into communication with another channel 25 through which fluid pressure is introduced behind the pistons in order to throw them outwardly and into such a position that the openings therein will register with the grooves as each piston reaches and passes the abutment. As soon as each piston passes the abutments, its slot again communicates with the channel 26 and the piston is pressed back into the slot.

In rapidly rotating mechanism the slides may be caused to move outward by the centrifugal force, so that in some cases the action of the fluid pressure supplied through the channel 25 can be dispensed with, or the inward movement could be imparted to the piston by a constant pressure introduced into the space between the rotating member and the cylindrical casing. This pressure would of course be so regulated, as to overcome the centrifugal force but to be overcome by the intermittent pressure acting upon the inner faces of the widened parts of the pistons. In this case the pressure channel 26 could be dispensed with.

In Fig. 7, the development illustrates a form similar to the embodiment shown in Figs. 1 to 3, except that the surfaces which guide the pistons are not parallel but are symmetrical, in which there are a double set of pistons and in which there is a fluid pressure medium for keeping each set of pistons in contact with the corresponding surface. A central channel 20 supplies pressure to both sets of pistons and each piston in one set is preferably provided with a shoulder or projection 21 which, when the corresponding pistons in each set are forced inwardly by the surfaces, abuts closely against the opposite piston. In this way the pressure of the fluid medium upon the pistons may be reduced, while they pass the abutments.

It will be seen that in all the forms of the mechanism with guiding-cam surfaces as above described, the said cam-surfaces are so arranged that there is no relative motion between the rotating member and each blade during the time that the said blade is supporting the pressure of the driving fluid in the case of a motor or of the driven fluid in the case of a pump. For this purpose in the arrangement shown in Figs. 1-3 and 7 the parts of cam-surfaces bounding the wide parts of the chambers 6 and 7 are parts of circular ring surfaces lying in planes perpendicular to the axis of rotation of the rotating member, see Fig. 3. Also in Figs. 4 and 5, the cams 3 and 4 have surfaces concentric to the axis of the rotating member at the places where there is unbalanced pressure on the blades. By this means wear of the mechani-

ism is reduced to a minimum especially when working under heavy pressures. It is obvious however that the said blades may be arranged to be moved when under pressure, 5 for example, in certain kinds of air-compressors where low pressures are employed.

Various changes may be made in the several constructions illustrated and various other embodiments of the improvements 10 may be had, without departing from the spirit of the invention.

It will be understood that any suitable fluid pressure medium may be employed and that the improvements may be applied to all 15 forms of motors or pumps without limitation. It will also be understood that the particular number of pistons illustrated in the accompanying drawings is arbitrary and not essential.

20 I claim as my invention:

1. In a rotary engine, the combination of a rotary member having a groove, a fixed abutment therein, a piston adapted to slide across the groove and having an opening so 25 as to be capable of passing the abutment and a casing having a cam surface upon which the piston travels with one of its end faces.

2. In a rotary engine, the combination of a rotary member having a groove, an abutment 30 therein, a sliding piston athwart the groove and having an opening so as to be capable of passing the abutment, and a casing having a surface upon which the piston

travels and adapted to form with the rotary member and piston a working chamber.

3. In a rotary engine, the combination of a rotary member having a groove, an abutment 35 therein, a sliding piston athwart the groove, and parallel surfaces between which the piston is guided, said piston having an opening which is brought into register with the grooves as the piston reaches and passes the abutment.

4. In a rotary engine, the combination of a rotary member having concentrically arranged grooves in one end surface, fixed 45 abutments therein, a piston adapted to slide radially across the grooves and having openings therein and means to bring the openings into register with the grooves as the piston reaches and passes the abutments.

5. In a rotary engine, the combination of a rotary member having concentrically arranged grooves in both end surfaces, fixed 55 abutments therein, pistons adapted to slide radially across the grooves and having openings therein, and means to bring the openings into register with the grooves as the pistons reach and pass the abutments.

In testimony whereof I have signed my 60 name to this specification, in the presence of two subscribing witnesses.

JULIUS WILHELM VON PITTLER.
